UNITED STATES PATENT OFFICE

2,488,894

SOCKET WRENCH WITH NUT EJECTOR

John Stephen Barrett, Minneapolis, Minn., assignor of one-half to Ralph C. Jurgensen, Minneapolis, Minn.

Application December 22, 1945, Serial No. 636,763

3 Claims. (Cl. 81—124.1)

1

My present invention relates to socket wrenches, and has as an important objective the provision of an improved socket wrench wherein means is provided for assisting in removal of a nut from the socket. In carrying out this important feature of the invention, I provide within the socket wrench head a yieldingly outwardly-biased nut-projecting plunger that is mounted for reciprocating movements into and out of the nut-receiving socket of the wrench head, whereby a nut in operative position in the socket will be yieldingly urged toward the open end of the socket. Preferably, and in accordance with the preferred embodiment of the invention herein illustrated, I provide stop means for positively limiting outward projecting movements of the plunger into the nut-receiving portion of the socket to less than the axial length of the nut-receiving portion of said socket, whereby the yieldingly biased plunger will automatically project a nut from the socket sufficiently to permit easy gripping of the nut with the fingers for manual removal of the nut, but will not completely eject the nut from the socket unless the socket be downwardly tipped for the purpose. Also, with the ejecting or projecting movement of the plunger thus limited, a nut seated in the outer portion of the socket may be retained therein for application to a bolt without any effort on the part of the operator.

Another important objective of the instant invention is the provision, in a wrench of the kind above described, of a nut-projecting plunger provided with an outwardly-opening bolt-receiving aperture adapted to receive the end of a bolt extending beyond the end of a nut to which the socket is applied for application or removal of the nut from the bolt, whereby to reduce to a minimum the space in the wrench head necessary to accommodate the nut-projecting parts. In the preferred embodiment of the invention illustrated, I further reduce the space consumed by the nut-projecting unit or parts by employing a helicoidal compression spring as a plunger-biasing means, whereby the spring can be compressed to the thickness of the wire from which it is wound.

Still another important objective of the invention is the provision of an improved nut-projecting socket wrench wherein the nut-projecting plunger and the biasing means therefor are a self-contained unit which may be inserted into and removed from the socket head as such. To this end, I preferably mount the plunger and its biasing means (usually a compression spring)

2

in a suitable retainer cage with which the plunger and biasing means are insertable into and removable from the wrench head as a self-contained unit. In accordance with the preferred embodiment of the invention herein illustrated, the stop means for limiting outward projecting movements of the plunger is formed as part of the retainer cage.

The above and other highly important objects 10 and advantages of the invention will be made apparent from the following specification, claims, and appended drawings.

In the accompanying drawings, like characters indicate like parts throughout the several 15 views.

Referring to the drawings:

Fig. 1 is an axial sectional view, through a socket wrench embodying the invention and showing the same in operative position on a nut;

20 Fig. 2 is an axial sectional view corresponding to Fig. 1 but showing the nut partially projected from the wrench socket as prior to or following a work operation; and

Fig. 3 is a transverse sectional view taken on 25 the line 3—3 of Fig. 2.

In the drawings, a socket wrench head involving a preferred form of the invention is indicated as an entirety by 1 and the shank of the wrench is indicated by 2. In accordance with standard 30 practice, the wrench head 1 is provided in one end portion with an angular recess 3 for receiving a correspondingly-shaped end of the shank 2 for removable application of the wrench head to the shank. Also shown in the drawings is a threaded bolt 4 having a nut 5 applied thereto. The bolt 4 is shown as being extended from a 35 part 6.

The wrench head 1 is provided with the customary nut-receiving socket 7 opening through the 40 end thereof opposite the shank 2. For reception of the nut-projecting elements of the invention, the wrench head 1 is provided inwardly of the nut-receiving socket 7 with an axial recess 8 that opens outwardly into the nut-receiving socket 7. Recess 8 is preferably cylindrical and opens inwardly into the shank-receiving recess 3, but is preferably of somewhat greater diameter than the recess 3 to provide a seat 9.

The nut-projecting plunger, indicated by 10, 50 is shown as being provided with an outwardly-opening axial bolt-receiving aperture 11. Adjacent its inner end, the plunger 10 is shown as being provided with a radically-projecting stop flange 12. As previously indicated, the plunger 55 10 is yieldingly urged outwardly by a yielding

biasing means which is preferably in the nature of a helicoidal compression spring 13.

As was also previously indicated, the plunger 10 and its biasing spring 13 are preferably assembled as a unit prior to insertion into the wrench head. The retainer that maintains the plunger 10 and spring 13 as a unit is shown as being in the nature of a tubular cylindrical shell 14 having a radially-inturned spring-seating flange or stop element 15 at its inner end and a radially inwardly-turned stop flange 16 at its outer end for cooperation with the stop flange 12 of the plunger 10. The plunger 10 is telescopically slidable in the cage 14 for reciprocating movements into and out of the nut-receiving socket 7 and is yieldingly-urged in an outward projected position by the spring 13, which is compressed between the cage seat 15 and the base of plunger 10. As will be seen particularly by reference to Fig. 2 of the drawings, outward projecting movements of the plunger 10 into the nut-receiving socket 7 are definitely limited by engagement of plunger stop flange 12 with cage stop flange 16 to a position wherein the nut 5 projects sufficiently beyond the end of the socket to be easily gripped by the fingers for complete removal. It is also important to note in connection with Fig. 2 that the nut, when projected by the plunger, is sufficiently seated in the socket 7 to be retained therein unless the wrench be tipped downwardly from the horizontal for intentional displacement of the nut. By reference to Fig. 1, it will be seen that the spring 13, being of the helicoidal type, can be compressed to the thickness of the cross-section of the wire from which it is formed, so that a minimum of space will be consumed in the wrench head by the nut-projecting or ejecting unit.

In the wrench illustrated, and preferably, the retainer cage 14 is press fitted into the aperture 8.

What I claim is:

1. In a socket type wrench, a head having a

nut-receiving socket therein and a recess therein opening axially into said socket, a cage press fitted into said recess, a nut-projecting plunger working telescopically in said cage for sliding movements into and out of the socket, a coil compression spring in said cage yieldingly biasing said plunger in the direction of the socket, and stop means on the cage and plunger definitely limiting outward projecting movements of the plunger.

2. The structure defined in claim 1 in further combination with a stop flange adjacent the inner end of the cage and against which the inner end of the spring is seated, whereby to provide a self-contained nut-projecting unit prior to insertion into the recess of the socket.

3. In a socket type wrench, a head having a nut-receiving socket therein and having a recess opening axially into said socket, a thin metallic retainer cage press fitted into said recess, a nut-projecting plunger having a radially-projecting stop flange at its inner end which is telescopically mounted in said retainer cage, a cooperating radially-inturned stop flange on the outer end of the retainer cage for limiting the outward movement of the plunger into the socket, said retainer cage also having an inturned flange at its inner end, and a compression spring of the helicoidal type interposed between the last said stop flange and the nut-projecting plunger.

JOHN STEPHEN BARRETT.
